UNITED STATES PATENT OFFICE

2,257,502

PRINTING PRESS

Joseph F. Jirousek, Cleveland, Ohio, assignor to
 The Chandler & Price Company, Cleveland,
 Ohio, a corporation of Ohio

Application January 5, 1938, Serial No. 183,476

3 Claims. (Cl. 101—232)

This invention relates, as indicated, to printing presses, but has reference more particularly to improvements in the lithograph or offset press described in my Patent No. 2,109,486, and my co-pending patent application Serial No. 19,688, filed May 3, 1935. This application is a continuation in part of the aforesaid patent and application.

Among other objects of the invention is the provision of a press of the aforesaid character which will operate in a continuous manner and at high speeds, and which is of compact, rugged construction.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical means in which the principle of the invention may be used.

In said annexed drawings:

Fig. 1 is a side elevational view of a press embodying the novel features of the invention;

Fig. 2 is a plan view of the press;

Fig. 3 is a transverse cross-sectional view of the press, taken on the line 3—3 of Fig. 2;

Fig. 4 is a perspective view of a portion of the sheet feed plate;

Fig. 5 is a fragmentary side elevational view, showing mechanism for actuating the side-gauging and other devices associated with the press;

Fig. 6 is a longitudinal cross-sectional view of the press, taken on the line 6—6 of Fig. 3;

Figs. 7 and 8 are views showing more or less diagrammatically the actuation of the grippers of the impression cylinder;

Figs. 9, 10, 11 and 12 are fragmentary views showing the actuation of the gripper fingers of the sheet-delivery conveyor;

Fig. 13 is a fragmentary view showing adjusting means for the impression cylinder;

Fig. 14 is a fragmentary view showing means for eliminating backlash in the gearing driving the impression cylinder;

Fig. 15 is a view showing means for permitting circumferential adjustment of the lithograph plate cylinder;

Fig. 16 is a view, partly in section and partly in side elevation, of the water-supply or fountain; and

Fig. 17 is a cross-sectional view, taken on the line 17—17 of Fig. 16.

Referring more particularly to the drawings,

the press is seen to comprise a framework 2 of suitable construction, in which are mounted an impression cylinder I for carrying paper to be printed or lithographed and a transfer cylinder T, the transfer cylinder being below the impression cylinder and in generally vertical stack arrangement therewith. In addition, a lithograph plate cylinder L is conveniently arranged below the impression cylinder and is adapted to be driven in step with the cylinders I and T.

The cylinder L is driven by means comprising an electric motor 3, endless belt 4, flywheel or pulley 5, drive shaft 6, and pinion 7. The cylinder L, in turn, drives the cylinders T and I, all of the cylinders being suitably intergeared with each other.

The impression cylinder I is supplied with paper from a supply feed table 8, which is fed upwardly step by step as the sheets are removed from the top of the stack and suitable mechanism for thus elevating the feed table, for removing the sheets therefrom and for feeding the sheets towards the impression cylinder are described at some length in the aforesaid co-pending application, Serial No. 19,688. However, instead of using rollers, as shown in said application, to convey the sheets from the feed table to the impression cylinder, a series of laterally spaced endless driven tapes 9 (see Figs. 1 and 6) are employed for this purpose.

The sheets are carried by the tapes 9 onto a feed plate 10, and continue in motion on such plate until their leading edges strike stop gauges 11, which are disposed below the cylinder I. These stop gauges are mounted on a bar 12 which extends transversely of the press and is mounted for vertical sliding movement in brackets 13 which are secured to the frame of the press. The bar 12 is normally maintained in its uppermost position by means of expansion coil springs 14, which are interposed between the ends of the bar and angle brackets 15 secured to the brackets 13, and when the bar is in this position, the stop gauges are in sheet gauging position. When the sheets are thus gauged, they are in position to be seized by the grippers of the impression cylinder, as will be presently described.

In order to permit the sheet to be thus seized or gripped, and to be removed from the feed plate 10, the bar 12 is adapted to be periodically lowered, and for this purpose the following means is provided. A rock shaft 16 is journalled in the brackets 13 and has keyed thereto a lever 17, the forward end of which engages the upper edge of the bar 12, as shown in Fig. 6. The shaft 16

also has keyed thereto a lever 18, carrying at its upper end a cam roller 19. The cam roller 19 bears against a cam 20 mounted on the shaft 21 of the impression cylinder, so that with each revolution of said cylinder, the gauges 11 will be depressed just below the upper surface of the plate 10.

As the sheet proceeds from the tapes 9 to the aforesaid stop gauges it is also accurately gauged in a lateral direction and for this purpose mechanism is employed which is clearly shown in Figs. 2, 3 and 5. Such mechanism includes right and left register plates 22 and 23 respectively, each having a register finger 24 which extends downwardly into a slot 25 in the plate 10. Each of the plates 22 and 23 has secured thereto a pair of pins 26 which extend through a bracket 27. One of the brackets 27 is secured to a shaft 28, as by means of a set screw 29 and the other bracket is similarly secured to a shaft 30. The shafts 28 and 30 are parallel and spaced from each other, and their inner overlapping ends have rack portions 31 and 32 respectively, which are in mesh with a pinion 33. The shafts are mounted for reciprocal movement in a bracket 34 which is secured to the center of a cross-bar 35, the ends of which are bolted to upright portions of the frame of the press. The pinion 33 is revolvable on the bracket 34. The outer portions of the shafts 28 and 30 extend through the openings provided therefor in the frame of the press, the shaft 28 extending beyond the frame, as shown in Fig. 3, and into engagement with a surface cam 36 mounted on the inner face of a holder 37. The holder 37 is revolvably mounted on a stub shaft or pin 38, which is secured to a bracket 39, secured as at 40 to the frame of the press.

The cam holder 37 has secured to its outer surface a drive sprocket 41, which is driven through the intermediary of a sprocket 42, keyed to the shaft 21 of the impression cylinder, and a chain 43.

The shaft 30 also extends beyond the frame, as shown in Fig. 3, and carries at its outer end a collar 44, between which and the frame is interposed a compression coil spring 45. This spring serves to force the shaft 30 and therefore the gauge plate 23 to their outermost positions, and also acts, through the rack 32, pinion 33 and rack 31, to normally maintain the shaft 28 and gauge plate 22 in their outermost positions, the shaft 28 being thus maintained in constant engagement with the cam 36.

It will be apparent from the foregoing description that with each revolution of the impression cylinder, the gauge plate 22 is moved laterally to gauge the sheet laterally, assuming that the gauging is from the right to the left, as viewed from the cylinder or front end of the press. For right to left gauging, the gauge plate 23 is moved to the left sufficiently to avoid striking of this plate by the sheet while being gauged by the plate 22. For left to right gauging, the gauge plate 22 is similarly moved to the right sufficiently to avoid being struck by the sheet during gauging thereof by the plate 23. For the purpose of thus moving the gauge plates, as well as to provide for accurate adjustment thereof, each plate is adapted to be moved by means of an adjustment screw 46 which is secured at one end to the plate and is in threaded engagement with the bracket 27. It will be understood that with each gauging movement, the plates 22 and 23 approach each other, but one of the plates will

be non-effective for gauging purposes, as already described.

In order to facilitate side gauging of the sheets, particularly thin sheets which are likely to curl, it is desirable to stiffen the sheet laterally while it is thus being gauged. For this purpose, mechanism is employed, consisting, as shown in Figs. 2, 3, 5 and 6, of a bar or roll 47 which extends transversely of the press directly below the shafts 28 and 30, and is supported at its ends in brackets 48 which are carried by holders 49. The holders 49 extend through apertures in brackets 50 which are secured to the cross-bar 35, and have enlarged upper portions 51, between which and the bracket are interposed compression coil springs 52. These springs serve to normally maintain the bar 47 in its uppermost position, as shown in solid lines in Fig. 6. The portion 51 of each holder 49 is slotted and supports a roller 53 which, by means of the spring 52 is constantly maintained in engagement with a cam 54 eccentrically mounted on a rock shaft 55. The shaft 55 is rocked or oscillated by means of a cam 56, which is secured to the shaft 21 of the impression cylinder, through the intermediary of a cam roller 57, lever 58 and lever 59. The lever 58 is pivoted as at 60 to the frame of the press, and the lever 59 is keyed to the shaft 55. Upon each revolution of the impression cylinder, the roller 47 will thus be depressed to the position indicated in dotted lines in Fig. 6, in which position it will crimp the sheet S slightly in a transverse direction, as shown, so that that sheet, as it is side-gauged, will have sufficient stiffness to resist curling thereof. This crimping or corrugating of the sheet continues throughout the gauging operation.

Following the gauging of the sheet, the sheet is ready to be seized by the grippers of the impression cylinder, but just prior to thus being gripped, and to avoid shifting of the sheet from its gauged position, the sheet is momentarily held stationary by means of suction shoes 60, which communicate with a suction manifold 61. Suction is periodically created in the suction manifold 61 by means which are described in my application Serial No. 19,688, and which will not therefore be further described herein. In the present construction, however, the suction manifold and shoes are stationary instead of being movable as in the aforesaid application.

The impression cylinder is of a construction similar to that described in my U. S. Letters Patent No. 2,058,888, and comprises a strip 61 of hardened steel, and a multiplicity of grippers 62 having beaks 63 between which and the strip 61 the forward edge of the sheet is adapted to be gripped. The grippers are carried by a rock shaft 64 which is mounted in the ends of the cylinder. One end of the shaft 64 projects beyond the end of the cylinder and is provided with a tumbler 65 having a cam groove 66 in its outer surface. This tumbler is utilized for closing the grippers when the sheet is to be removed from the feed plate 10 and for opening the grippers to release the sheet after the printing operation. The closing and opening of the grippers is diagrammatically illustrated in Fig. 8, wherein the numerals 67 and 68 designate pins extending parallel with the axis of the impression cylinder and carried by a bracket (not shown) secured to the frame of the press adjacent one end of the cylinder.

As the impression cylinder, which rotates in a clockwise direction, as viewed in Figs. 6, 7 and 8, approaches the sheet-receiving position, the

tumbler 65 occupies the position shown in solid lines in Fig. 8, in which position of the tumbler the grippers will be open, and disposed within the cylinder body, as indicated in dotted lines behind the tumbler. At this time, the grippers are maintained in the open position by means of the toggle mechanism shown in Fig. 7, and comprising a toggle arm 69 which is keyed to the shaft 64, a toggle arm 70 pivoted to the arm 69 and extending through a rocker pin 71 mounted on the end of the cylinder, and a compression coil spring 72 mounted in the arm 70 between the pin 71 and an enlarged end portion of the arm 70. The parts of the toggle mechanism at such time occupy the position indicated by the dotted lines.

Upon continued movement of the cylinder, the pin 67 engages the outer wall of the cam groove 66 of the tumbler, forcing the tumbler to literally somersault to the position shown in dotted lines, in which position of the tumbler, the gripper 62 will have moved to the closed position, as indicated by the dotted lines, and as clearly shown in Figs. 6 and 7, the forward gauged edge of the sheet being thus gripped between the grippers and the strip 61. Due to the presence of the toggle mechanism, the grippers will be closed by a sudden snap action, which has been found desirable and necessary in view of the short interval of time available for such closing. The position of the various parts of the toggle mechanism following the closing of the grippers is shown in solid lines in Fig. 7. To permit passage of the beaks 63 of the grippers during the gripper closing movement, the feed plate 10 has slots or recesses 73 formed in its forward edge, as shown in Fig. 4.

When the tumbler 65 reaches the position shown in dash lines in Fig. 8, the pin 68 engages the inner wall of the cam groove 66 of the tumbler, forcing the tumbler to somersault to the position shown in dot and dash lines, in which position of the tumblers, the grippers 62 will have been snapped to their open position, thereby releasing the forward edge of the sheet.

For the purpose of transporting the sheets, when thus released, to a point of delivery, conveyor mechanism, shown most clearly in Figs. 1, 3, 6 and 9 to 12 inclusive, is employed. Such mechanism comprises a pair of laterally spaced endless conveyor chains 74 and 75 disposed above the impression cylinder and extending rearwardly of the press above the sheet-feeding mechanism. The forward portion of these chains are carried by sprockets 76 which are mounted on a shaft 77 journaled in the frame of the press. The central portions of the upper and lower runs of the chains are supported by idler sprockets 78, and the rear portions of the chains are carried by sprockets 79 mounted on a shaft 80 journaled in the rear ends of an overhanging or outrigger support 81 secured to the main frame 2. The conveyor chains are driven in the direction indicated in Fig. 1 by suitable driving mechanism comprising a bevel gear 82 at one end of the shaft 21 of the impression cylinder, bevel pinions 83 mounted for rotation on a bracket 84 secured to the frame of the press, and a bevel gear 85 secured to one end of the shaft 77.

Secured to the conveyor chains at suitably spaced points therealong are bars 86 which extend transversely from one chain to the other and are provided with a multiplicity of spaced stationary gripper fingers 87. Each bar 86 has upturned ends 88 which form bearings for a rock

shaft 89, the intermediate portion of which is of square cross-section and has secured thereto a multiplicity of flexible gripper fingers 90, corresponding in number and spacing to the fingers 87, and which flexible gripper fingers are adapted to cooperate with the fingers 87 to grip the edge of the printed sheet upon release thereof from the impression cylinder.

As each of the bars 86 approaches the impression cylinder, see Fig. 6, the gripper fingers 90 are maintained in open position by means of toggle mechanism, shown in Fig. 11, and comprising a toggle arm 91 affixed to a portion of the shaft 89 which extends beyond one of the upturned ends 88 of the bar 86, a toggle arm 92 pivoted to the arm 91 and extending through an aperture in an angle bracket 93 secured to one end of the bar 86, and a compression coil spring 94 mounted on the arm 92 between the bracket 93 and an enlarged end portion of the arm 92. The parts of the toggle mechanism at such time occupy the position shown in solid lines.

As the bar 86 moves adjacent the impression cylinder, see Fig. 9, a pin 95, which extends outwardly from a bracket 96 rigidly secured to one end of the shaft 89 enters a cam groove 97 in a cam 98 which is secured to the frame of the press adjacent one end of the cylinder. This cam groove is so shaped as to move the pin 95 sufficiently to cause the bracket 96 to rotate in a clockwise direction, as viewed in Fig. 9, thereby rocking the shaft 89 and closing the gripper fingers 90 on the fingers 87, to thereby grip the edge of the leading edge of the printed sheet which is at this time released by the grippers 62. The gripper fingers are closed by a snap action resulting from the aforesaid toggle mechanism, and are maintained in such position by such toggle mechanism, the parts of which occupy the position shown in dotted lines in Fig. 11.

As the sheet S is carried rearwardly by the conveyor, its trailing portion is maintained in elevated position, as shown in Fig. 10, to avoid dragging of the same on the impression cylinder and adjacent parts of the press. For this purpose, mechanism is employed which is clearly shown in Figs. 5, 6 and 10. Such mechanism comprises an elevator bar or roller 99 which is supported on rods 100 mounted for reciprocable movement in bearings 101 on the frame of the press. These rods are pivoted at their lower ends to levers 102 which are keyed to a rock shaft 103, the ends of which are journaled in the frame of the press. The bar 99 normally occupies the inoperative position shown in Figs. 6 and 9, but is periodically moved to the operative or sheet-sustaining position shown in Fig. 6 and held in such position by means comprising a cam 104 on the shaft 21, cam roller 105, a lever 106 on which the roller 105 is mounted, this lever being pivoted as at 107 to the frame of the press, a link 108 and a lever 109, the latter being keyed to the shaft 103. Supplemental means, such as the guard strips shown in my Patent Serial No. 2,109,486, may be arranged under the conveyor to prevent the trailing portions of the sheets from becoming entangled in the mechanism below, as the sheets are carried to the rear of the press.

As each sheet approaches the rear end of the press, the bracket 96 engages a trip pin 110 which extends from the frame of the press, thereby causing the bracket and shaft 89 to rotate in a counter-clockwise direction, as viewed

in Fig. 12, thus opening the gripper fingers 90 and releasing the sheet.

The released sheets fall onto a delivery table 111, arranged to be lowered step-wise as the printed sheets are deposited thereon. Mechanism for thus lowering the delivery table in synchronism with the elevation of the feed table is described in my Patent No. 2,109,486, and need not be detailed herein. By providing the delivery table with castors 112, the table may be run off on the floor as desired, when lowered into full discharge position. The table is disposed within a discharge frame 113, and when in position within this frame, is maintained in proper vertical alignment by guide-engagement with the frame.

For general convenience, and especially for allowing access to the feed table, the discharge frame 113 may be mounted to swing laterally from alignment with the main frame 2. Thus the frame 113 may be connected to the main frame by means of hinge-connections 114. These allow the entire frame 113, with its contained delivery table 111 to be swung laterally, the initial swing-out position thereof being indicated in dotted lines in Fig. 2, and the construction allowing swing-out to the full extent to give clear access to the portions of the press above and forwardly of the delivery frame.

By employing such pivotally mounted delivery table frame the operator is enabled to gain access to the feed table for loading, or a pre-loader device such as that disclosed in applicant's co-pending application Serial No. 231,034, now Patent No. 2,213,736, may be employed. Such pre-loader is pivotally attached to the side of the press opposite to that of the pivotal attachment of the delivery table frame so that as such delivery table is swung laterally out of the way the pre-loader may be swung into position. The empty feed table is removed and the new loaded feed table moved forwardly from the pre-loader into position to be elevated by the feed table elevating mechanism, all as more fully described in the above-identified patent. Or, the feed table may be loaded by hand after swinging the delivery table out of the way. Either method of loading requires ready access to the rear of the feed table frame which is provided by the delivery conveyor outrigger support and laterally swingable delivery table.

Means have been provided, as shown in Figs. 5 and 13, for adjustment of the impression cylinder with relation to the transfer cylinder. Such adjustment is obtained by journalling the shaft 21 of the impression cylinder in eccentric bushings 115 mounted in the frame 2, these bushings having arms 116 extending from the outer ends thereof. Pivoted secured to the ends of these arms are adjusting screws 117, which extend vertically upward and are in threaded engagement with lugs 118 on the press frame 2. The screws 117 have knurled knobs 119 secured to their upper ends, whereby the screws may be manipulated to rock the bushings 115 to any desired position so as to adjust the impression cylinder with respect to the transfer cylinder. The adjusted portion may be maintained by means of knurled lock nuts 120 which are mounted on the screws 117 and are movable into abutment with the upper surfaces of the lugs 118.

In order to eliminate backlash in the gearing driving the impression cylinder when the impression cylinder is adjusted away from the transfer cylinder T, the helical driven gear at the

end of the impression cylinder may be in the form of a split gear wheel, one part 121 (Figs. 2 and 14) being fixed to the impression cylinder, and the other part 122 being circumferentially adjustable with relation to the part 121, bolts or cap-screws 123 taking through arcuate slots 124 into the gear part 121. On being loosened, the movable gear portion 122 can be turned sufficiently to, in effect, tighten the teeth of combined parts 121, 122, in the teeth of coacting driving gear 125 of the transfer cylinder T, the gear portions 121, 122, upon tightening of the bolts 123 then working together as a single gear. In this way, backlash is eliminated.

To permit circumferential adjustment of the lithograph plate cylinder L, the helical driving gear 126 on the end of said cylinder has arcuate slots 127 therein, through which bolts or cap-screws 128 take into the cylinder. When these bolts are loosened the cylinder may be circumferentially adjusted and, on tightening the bolts, the position of the cylinder relative to the gear 126 is maintained.

Water is supplied to the lithograph plate cylinder L by means shown in Figs. 16 and 17. Such means comprises a frame 129 mounted on a bracket 2a of the frame 2 which supports a water fountain 129a from which water is picked up by a pick-up roller 130 mounted on a shaft 131 which is journaled in bearings 132 on the frame 129. A carrier roller 133 is mounted on a pair of swing levers 134 which are keyed at their lower ends to a rock shaft 135 journaled on the frame 129. These levers are intermittently operated by a cam consisting of two cam members 136 and 137 mounted on the shaft 131, and which bears against a cam roller 138 carried by a lever 139 which is keyed to the shaft 135. In this way, the carrier roller 133 is alternately contacted with the pick-up roller 130 and the distributor roller 140, supplying the cylinder-contacting rollers 141.

The period or length of dwell of the carrier roller 133 on the roller 130 may be varied to vary the amount of water taken up from the fountain. For this purpose the cam member 137 is circumferentially adjustable about the shaft, and with relation to the cam member 136. To secure this adjustment, the cam member 137 is secured to a sleeve 142 on a reduced end portion of the shaft 131, and the sleeve may be rotated by means of a worm 143 and a worm wheel 144, the latter being keyed to the sleeve. The worm 143 may be actuated by means of a handwheel (not shown). By loosening the set screw 145, the cam member 137 may set at any desired position with relation to the cam member 136 so as to give the length of dwell required, and by then tightening the screw 145, the adjustment is maintained.

The frame 129 is mounted so as to be slidable away from the cylinder L, and to facilitate such retraction of the frame, it is provided with a pinion 146, in mesh with a rack 147 on the bracket 2a, the pinion being rotatable by means of a handwheel (not shown). The frame is locked or latched in its normal or working position by means of a locking lever 148, which is pivotally mounted on an eccentric bushing 149 mounted on a stub shaft 150 extending from the frame 2, the lever engaging a pin 151 which extends from the frame 129. To retract the frame 129, the lever 148 is first swung upwardly and rearwardly by means of a knob 152 thereon provided.

The frame 129 may be slightly withdrawn into inoperative position without disturbing the lever

148 by merely turning the eccentric bushing 149, a hand crank 153 being provided for this purpose.

In view of the foregoing detailed description of the various novel features of the press, the operation of the press will be apparent, and need not be further described.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a printing press, an impression cylinder, a pivotally mounted delivery table rearwardly spaced therefrom, a rearwardly movable feed table between said cylinder and said delivery table, a sheet conveyor running from said impression cylinder to said delivery table and passing above said feed table, and an outrigger support for said conveyor extending over said delivery table, to permit swinging of said delivery table.

5 2. In a printing press, an impression cylinder, a removable delivery table rearwardly spaced therefrom, a rearwardly movable feed table between said cylinder and said delivery table, a conveyor running from said feed table to said cylinder, a delivery conveyor above said feed table and first named conveyor and running from said cylinder to said delivery table, and an outrigger support for said delivery conveyor extending over said delivery table, whereby said delivery table may be removed and access had to said feed table.

10 3. In a printing press, an impression cylinder, a delivery table rearwardly spaced therefrom and mounted for movement laterally of the press, a rearwardly movable feed table between said cylinder and said delivery table, a sheet conveyor running from said impression cylinder to said delivery table and passing above said feed table, and an outrigger support for said conveyor extending over said delivery table to permit removal of said delivery table when so desired, and also to permit access to said feed table.

JOSEPH F. JIROUSEK.
